US00D616828S

(12) **United States Design Patent**
Tung et al.

(10) **Patent No.:** US D616,828 S
(45) **Date of Patent:** ** Jun. 1, 2010

(54) **ELECTRICAL CONNECTOR**

(75) Inventors: **Chang-Hsien Tung**, Tu-Cheng (TW);
Kuo-Chun Hsu, Tu-Cheng (TW);
Yu-Hua Mao, Kunshan (CN)

(73) Assignee: **Hon Hai Precision Ind. Co., Ltd**, Taipei
Hsien (TW)

(**) Term: **14 Years**

(21) Appl. No.: **29/345,608**

(22) Filed: **Oct. 20, 2009**

(30) **Foreign Application Priority Data**

Jul. 2, 2009 (CN) 2009 3 0308287

(51) **LOC (9) Cl.** 13-03

(52) **U.S. Cl.** D13/147; D13/154

(57) **CLAIM**

The ornamental design for an electrical connector, as shown and described.

DESCRIPTION

FIG. 1 is a front, top and right side perspective view of an electrical connector showing our new design;

FIG. 2 is a front elevational view thereof;

FIG. 3 is a rear elevational view thereof;

FIG. 4 is a left side elevational view thereof;

FIG. 5 is a right side elevational view thereof; and,

FIG. 6 is a top plan view thereof.

The broken line portion in the drawing views is included to show unclaimed subject matter only and forms no part of the claimed design.

1 Claim, 6 Drawing Sheets

FIG. 1

FIG. 2

FIG. 3

FIG. 4

FIG. 5

FIG. 6
